UNITED STATES PATENT OFFICE.

RUDOLF E. HELLMUND, OF SWISSVALE, PENNSYLVANIA, ASSIGNOR TO WESTINGHOUSE ELECTRIC AND MANUFACTURING COMPANY, A CORPORATION OF PENNSYLVANIA.

SINGLE-PHASE COMMUTATOR MOTOR.

Application filed January 26, 1917. Serial No. 144,663.

To all whom it may concern:

Be it known that I, RUDOLF E. HELLMUND, a subject of the German Emperor, and a resident of Swissvale, in the county 5 of Allegheny and State of Pennsylvania, have invented a new and useful Improvement in Single-Phase Commutator Motors, of which the following is a specification.

My invention relates to alternating-current commutator motors and particularly to motors that are adapted to operate either as substantially constant-speed or as adjustable-speed motors.

The object of my invention is to provide a 15 control system for motors of the character designated which shall permit the motors to be started and operated in either direction and produce particularly desirable commutating conditions and general operating 20 characteristics with a minimum of control apparatus.

It has heretofore been proposed to start motors of the above-indicated type as repulsion motors and to establish an auxiliary armature circuit after the motor reaches substantially synchronous speed. My invention provides a control system for a motor 25 of the character designated in which the magnetic axis of the armature is disposed at an angle relative to the main stator magnetic axis for starting and is brought into alignment with the magnetic axis of the 30 stator winding for running positions.

Figs. 1 and 2 of the accompanying drawings 35 illustrate my invention as applied to single-phase commutator motors having inductively-fed armature circuits. Fig. 3 illustrates a device for automatically changing the motor connections when certain operating conditions of the motor are reached. Figs. 4, 6, 9, 11, 13, 15, 17, 19, 21 and the corresponding switch-sequence charts shown 40 in Figs. 5, 7, 10, 12, 14, 16, 18, 20, and 22, illustrate the application of my invention to 45 motors of the doubly-fed type. Fig. 8 illustrates another application of my invention to motors of the doubly-fed type.

Fig. 1 of the drawings illustrates a motor 1 comprising a stator-field winding 2, an armature 3, and a plurality of armature brushes 4, 5, 6, and 7, and a plurality of control switches 8, 9, 10, 11, and 12 for governing the operation of the motor 1. The motor is adapted to be started into opera-

tion by establishing a magnetizing circuit 55 for the stator-field winding 2 from the supply-circuit conductors 18 and 19 and by completing a local circuit for the pair of brushes 4 and 5 of the armature 3. The switches 8 and 9 are closed to establish the 60 stator magnetic field, the magnetic axis of which is coincident with the axis of the stator winding 2, and the switch 10 is closed to establish an armature circuit which is angularly disposed relative to the magnetic 65 circuit of the stator.

With the connections established as shown, the motor will start as a repulsion motor and will have a starting torque which is very large and is dependent upon the angular relation between the magnetic axis of the winding 2 and that of the armature 3. When the motor reaches a predetermined speed, the switches 11 and 12 are closed to establish an auxiliary armature circuit, the 75 magnetic axis of which is symmetrically placed relative to the magnetic axis of the stator winding 2 and the brushes 4 and 5 and which, if combined with the magnetic flux produced by the current flowing in the 80 circuit for the brushes 4 and 5, will produce a resultant armature magnetic flux the axis of which is in alignment with the axis of the field winding 2. The motor, as now connected, is of the armature-excited type 85 and will operate at substantially constant speed. The speed may be changed, however, by changing the impedance of the external brush circuits or by shifting the position of the brushes. 90

Fig. 2 shows a modified form of the motor which is provided with three brushes 5, 6, and 7 instead of the form described in connection with Fig. 1. The brush 7 is made adjustable relative to the other two and is adapted to be shifted to the position shown in dotted outline to establish a magnetic axis for the armature at an angle to the stator magnetic axis for starting the motor. The brush 7 is first moved to the position shown in dotted outline. The switches 8 and 9 are then closed to establish a magnetizing circuit for the stator winding, and the switch 10 is closed to establish an external armature circuit between the brushes 5 and 7. 95 Since the magnetic axis of the armature is substantially in alignment with the brushes externally connected, it will lie at an angle 100 105

relative to the stator magnetic axis and will give the same starting characteristics that were secured in the motor illustrated in Fig. 1.

After the motor reaches a predetermined operating speed, the brush 7 is shifted to the position shown in solid outline. With the brush 7 in the running position, the magnetic axis of the armature and that of the stator are substantially coincident, and the motor is armature excited.

A centrifugal device, which automatically shifts the brush to the running position when the motor reaches a certain speed, is diagrammatically illustrated in Fig. 3, and comprises a motor armature 3 that is adapted to rotate a plurality of weights 20, an arm 21, which is pivoted on the motor shaft and is moved in accordance with the position of the weights 20, and a safety device 22 for preventing the closure of switches 8 and 9 when the arm 21 is in other than the "off" position. The arm 21 is provided with a brush 7, at one end, that is adapted to be moved by the arm 21 and a contact member 23, at the other end, that co-operates with a stationary contact member 24 to close the switch designated by 12 in Fig. 2. Motion is transmitted from the weights 20 to the arm 21 by means of a collar 25, a lever 26 and a link 27. As the motor-armature speed increases, the weights 20 are thrown outwardly and the brush 7 is moved from the position shown in solid outline to that shown in dotted outline. When the brush 7 reaches its final operating position, the switch 12 is closed by the engagement of the contact members 23 and 24. The safety device 22 comprises an arm which operates the switches 8 and 9 by its movement and has a latch 28 secured to one end thereof. When the weights are thrown outwardly, a pin 29 is raised and, if an attempt be made to close the switches 8 and 9, with the pin in this position, the pin will engage the latch 28 and prevent the closure of the switches 8 and 9. If, however, it is desired to open the switches 8 and 9 after the motor is operating, the latch swings back and allows the switches to be opened. A spring 30 maintains the latch in an upright position. The motor is thus protected from injuries incident to closing the switches 8 and 9 when the brush 7 is in the neutral or operating position. If it is desired to start the motor in a different direction, the link 27 may be connected to a point on the other side of the pivotal center of the arm 21. The brush 7 must occupy a starting position on the other side of the running position or substantially diametrically opposite from the brush 6 but must again be moved to the position shown in dotted outline when the motor is operating.

I desire it to be distinctly understood that the automatic control apparatus shown in

Fig. 3 is merely illustrative in character and may be radically modified in details, in actual practice, without departing from the spirit and scope of my invention.

Fig. 4 illustrates a double-fed motor 1 in which the field winding 2 is supplied from a portion 31 of a transformer winding, and the armature 3 is supplied from a portion 32 of the transformer winding. Fig. 5 is a chart showing the sequence of operation of the switches for the motor circuit illustrated in Fig. 4. For starting in one direction, the switches 10, 11, and 14 are closed which establishes a circuit for the field winding 2 and a circuit for the armature winding between the brushes 4 and 5 from the separate portions 31 and 32 of the transformer. The magnetic axis of the armature circuit between the brushes 4 and 5 is positioned at an angle relative to the magnetic axis of the field 2 and, therefore, the motor will have a large starting torque. For the running position, the switches 12 and 13 are closed which establishes an armature-exciting circuit between the short-circuited brushes 4 and 7 and 5 and 6. This again shifts the magnetic axis of the armature winding 3 into alignment with the magnetic axis of the stator winding, as in the transformer motors shown in Fig. 1 and Fig. 2. The motor shown in Fig. 4 may be started in the opposite direction by closing the armature switches 12 and 13 instead of switches 10 and 11 for the starting position. The dotted line shown is for a reverse doubly-fed connection or, in other words, for a connection wherein the voltage impressed upon the inducing field winding exceeds that impressed upon the armature and magnetizing field windings.

Fig. 6 illustrates a motor similar to that shown in Fig. 4 except that the armature is provided with three sets of brushes instead of four. For this motor, the armature circuit for starting is established from the brush 7 to the brush 5 by closing switches 8, 9, and 10. The switch 11 is closed after the motor reaches operating speed. Such a system of connections as that shown in Fig. 6 will not yield so large a starting torque as is provided by the connections shown in Fig. 4 but will reduce the number of switches required to control the operation of the motor since, in this case, only four switches are required, whereas, in the corresponding case illustrated in Fig. 4, seven switches are required. The brush 7 may be shifted by a device similar to that shown in Fig. 3 to provide a greater number of effective armature turns for starting if it is desired to secure a large starting torque.

Fig. 8 shows a motor in which the brush 7 is adapted to be shifted out of alignment with the stator field and in which the brushes 5 and 6 are permanently short-circuited by an

inductive reactor 33 which is adapted to inductively oppose the flow of exciting current between the brushes 5 and 6 but is substantially non-inductive, as regards the flow of a

5 working current from the brush 7 through the armature and the brushes 5 and 6 to the supply-circuit transformer 32. The direction of operation in this case is dependent upon the position of the brush 4 in start-

10 ing. This motor will have a small starting torque but will have substantially constant-speed operation after once being brought to the desired full-load speed, as previously

15 discussed with reference to Fig. 3. Fig. 9 illustrates a case in which the armature winding 3 and the cross-field winding 2 are grouped in shunt-circuit relation across the transformer winding 31. For starting, an

20 armature circuit is established through the brushes 4 and 5 and, for running position, an additional armature circuit is established through the brushes 6 and 7, as shown in the chart of Fig. 10. This is substantially

25 the same as the system of connections established in Fig. 4, as previously described. Fig. 11 illustrates a motor similar to that

30 shown in Fig. 9 except that three sets of brushes are provided instead of the four there illustrated. This figure will be readily

understood without further elaboration.

Fig. 13 illustrates a case in which an inductive reactor 33 is placed in series relation to the working circuit for the armature

35 and provides a short-circuiting path therefor in starting. The direction of starting of a motor so connected is dependent upon whether the switch 10 or the switch 11 is first closed. After operating speed is

40 reached, the switches 8, 9, 10, 11 and 13 are closed and the switch 12 is opened. This system of acceleration provides very good commutating conditions and smooth acceleration, with a large starting torque.

Fig. 15 discloses an application of the principles discussed in connection with Fig. 13, except that four sets of brushes are employed.

Fig. 17 shows a connection similar to that illustrated in Fig. 8 except that a short-circuiting connection is established across the brushes 5 and 6 by a switch 12 after the motor has reached full speed.

The circuit arrangements shown in Fig. 19 employ two reactors instead of the one discussed in previous figures. A circuit is first established through the reactors and the armature in series-circuit relation across the supply-circuit conductors. For full operating position, the reactors are non-inductive relative to the flow of load current therethrough but inductively oppose the flow of magnetizing current. In this connection, it may, at times, be desirable to wind the reactors upon a common core in order that, for starting conditions, the two portions of the

separate reactors may be made substantially non-inductive relative to the flow of load current at starting. Fig. 21 illustrates a motor which is adapted to start as a short-circuited repulsion motor and to have inductive reactors inserted in the circuit for the armature magnetizing current during operation. Either the switch 10 or 11 is adapted to be closed in the starting position for the armature 3 in accordance with the desired direction of operation. This establishes a magnetic circuit for the armature 3 the axis of which is in angular relation relative to the stator-field magnetic circuit and is brought into alignment with the magnetic axis of the stator-field winding by closing the switches 14 and 15. This motor has the same operating characteristics as that shown in Fig. 19.

It will be understood that, while the automatic controlling device shown in Fig. 3 is applied to the circuit arrangement shown in Fig. 2, my invention contemplates the application of such automatic controlling device, or its equivalent, to effect any or all of the adjustments involved in any of the other systems hereinbefore described.

Although I have described my invention as applied to only a few of the forms of single-phase commutator motors, I desire that only such limitations shall be imposed as are indicated in the appended claims.

I claim as my invention:

1. The combination with a dynamo-electric machine having a commutator comprising a plurality of brushes, and a field-magnet winding, of means dependent upon the operation of said machine for automatically changing the position of one of said brushes and maintaining the same in engagement with the commutator cylinder, auxiliary contact members adapted to be closed for a certain position of said movable brush, and interlocking means for preventing the establishment of a circuit for said field winding when said movable brush occupies certain positions.

2. The combination with a dynamo-electric machine having a commutator comprising a plurality of brushes, and a field-magnet winding, of means comprising a lever member the position of which is varied in accordance with the speed of the motor arranged to change the position of one of said brushes, and interlocking means actuated by said lever member for preventing the establishment of a circuit for said field winding when said movable brush occupies certain positions.

3. A single-phase commutator motor having a field winding, an armature winding, a commutator cylinder for said armature winding, a pair of brushes bearing upon said commutator cylinder and disposed substantially symmetrically with respect to the

axis of said field winding, a reactor adapted to be connected to said brushes, said reactor having a mid-tap, and an adjustable brush-means bearing upon said commutator cylinder and adapted to be electrically associated with said mid-tap for establishing a resultant armature field either at an angle to said field winding axis or in alinement therewith, according to the position of adjustment of said brush-means.

4. A single-phase commutator motor having a field winding, an armature winding, a commutator cylinder for said armature winding, a pair of brushes bearing upon said commutator cylinder and disposed substantially symmetrically with respect to the axis of said field winding, a reactor connecting said brushes, said reactor having a mid-tap, brush-means for establishing an unsymmetrical path through said armature winding from said mid-tap to a point out of alinement with said field axis, and brush-means for establishing a symmetrical path through said armature winding from said mid-tap, said last-mentioned path being

symmetrical and arranged parallel with respect to said field axis.

5. A single-phase commutator motor having a field winding, an armature winding, a commutator cylinder for said armature winding, a pair of brushes bearing upon said commutator cylinder and disposed substantially symmetrically with respect to the axis of said field winding, close-circuiting means for said brushes, an adjustable brush-means bearing upon said commutator cylinder and electrically associated with one of said first-mentioned brushes for establishing a resultant armature field either at an angle to said field winding axis or in alinement therewith, according to the position of adjustment of said brush-means, and automatic means for closing said close-circuiting means when said brush-means is in its second-mentioned position of adjustment.

In testimony whereof I have hereunto subscribed my name this 20th day of January, 1917.

RUDOLF E. HELLMUND.
